AUTOMATIC MULTIPLE BROACHING
MACHINE

John E. Lynch, Howard L. Pope, and Amos H. Hawley, Cincinnati, Ohio, assignors to The Cincinnati Milling Machine Co., Cincinnati, Ohio, a corporation of Ohio

Application November 15, 1935, Serial No. 49,986

17 Claims. (Cl. 90—33)

This invention relates to broaching machines and more particularly to an automatic multiple broaching machine.

One of the objects of this invention is to provide a broaching machine having a high productive capacity for small work pieces.

A further object of this invention is to provide an improved automatic multiple work loading and clamping mechanism for broaching machines.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a front elevation of a machine tool embodying the principles of this invention.

Figure 2 is a detail view of the right side of the machine showing a trip operable mechanism for the work loader.

Figure 3 is a section on the line 3—3 of Figure 1.

Figure 4 is a horizontal section on the line 4—4 of Figure 1.

Figure 5 is a vertical section on the line 5—5 of Figure 1.

Figure 6 is a section on the line 6—6 of Figure 4.

Figure 7 is a vertical section on the line 7—7 of Figure 1.

Figure 8 is a horizontal section on the line 8—8 of Figure 1 showing the mechanism for shifting the work holding slide.

Figure 9 is a horizontal section on the line 9—9 of Figure 1 showing the details of the work slide locking mechanism.

Figure 10 is a diagrammatic view of the hydraulic circuit of the machine.

Figure 11 is a detail view of the tripping mechanism.

In the drawings a vertical type broaching machine has been selected to illustrate the principles of this invention. This machine, as shown in Figure 1, comprises a bed or main support 10 upon which is formed a pair of vertical guide ways 11 and 12, and respectively receiving the vertically movable rams 13 and 14.

Means are provided for reciprocating the rams in opposite phase relation whereby when one ram is moving up on its return stroke the other ram is moving down on its cutting stroke. This makes

it possible to provide a first means for holding the work that is being broached and a second means into which the work may be loaded preparatory to the downward stroke of the other ram.

This machine is designed to broach simultaneously a plurality of work pieces during which time a similar number of work pieces are being simultaneously loaded in a second work holding means.

The work pieces illustrated at 15 in Figures 3, 4 and 5 may be small cylindrical shaped parts, in the end of which is to be broached a cross slot 16 which may be diametrically located on the end of the piece.

The machine is illustrated as having a capacity 15 for broaching four of these work pieces simultaneously, but it will be apparent from the description herein that the number may be increased or decreased, without changing in any way the principles of this invention.

As illustrated in Figure 6, a cross slide 17 is provided in which are formed eight work receiving passages 18, and dual clamps 19, 20, 21 and 22 are provided whereby two work pieces may be secured by depressing each clamp.

The particular construction of one of these clamps is shown in Figure 6 from which it will be seen that the clamping member 22 is provided with its guiding grooves 23 and 24 on opposite vertical sides thereof into which fit tongues 25 and 26 which are integral with the slide 17. A rod 27 is secured as by a pin 28 to the member 22 and has a sliding fit in a bore 29 formed in the slide 17. The rod has an enlarged head 30 which is adapted to slide in the enlarged bore 31. A spring 32 is enclosed in the bore 31 and acts against the head 30 to exert a continuous upward thrust on the clamping member 22 whereby it normally is held in a raised position so that the work receiving passages 18 are sufficiently enlarged to permit the insertion of work in a free and easy manner.

It will be noted from Figure 6 that the clamping member 21 is actually higher than clamping member 22 and that each of these clamping members has a beveled surface 33 and 34 respectively formed on the top thereof.

The clamping members 21 and 22 are automatically depressed when the slide 17 is moved toward the right, as viewed in Figure 6, by spring pressed plungers 35 and 36 respectively. Each plunger is mounted for reciprocation in a bore 37 formed in the fixed support 38. Each plunger has a reduced diameter 39 which is surrounded by a spring 40, whereby the spring continuously acts to move the plunger downward. The upper

end of each plunger is threaded at 41, which threaded portion passes through a reduced bore 42 formed in the member 38 and has a lock nut 43 adjustably positioned on the threaded end of the plunger to limit the extent of downward movement. It will be noted that the plunger 36 normally projects downward further than the plunger 35. The reason for this is that when the slide 17 is moved toward the right the clamping member 22 will pass beneath the plunger 35 without interference therewith with the result that the clamping member 22 will engage the roller 44 in the end of plunger 36 at substantially the same time that the beveled face 33 on member 21 engages the roller 44 on plunger 35. By means of this construction, members 21 and 22 will be depressed substantially at the same time so that four work pieces will be automatically clamped in working position at the same time.

20 When the member 17 is shifted toward the right the clamping members 19 and 20 will pass from beneath the respective clamping plungers 45 and 46, thereby automatically releasing the four work pieces held thereby.

25 From the foregoing it will be seen that merely shifting the slide 17 from one extreme position to the other will automatically effect clamping of one plurality of work pieces and a simultaneous unclamping of another plurality of finished work pieces.

30 The work supporting slide 17, as shown in Figure 3, rests upon a bearing surface 47 formed on the support 48 and is held against lateral movement by a gib 49. The member 17 also has an integral depending portion 50 which engages a guide surface 51 which holds the parts against any elevating movement.

35 The slide 17 is reciprocated by a lever 52, which as shown in Figures 3 and 8 is pivotally mounted at one end on the fixed pin 53 which serves as a fulcrum, and at the other end connected to the slide 17 through the following means. A bifurcated member 54 is secured to the slide 17 and has a squared block 55 pivotally mounted on the pin 40 56 and this block is engaged by the bifurcated end 57 of the lever 52. The construction is such 45 that relative movement in a radial direction may take place between the lever 52 and the block 55, still permitting the block to rotate about the 50 axis of pin 56 during longitudinal movement of the slide 17.

40 The lever 52 has an axially elongated slot 58 formed therein which is of sufficient width to receive a roller 59 pivotally mounted on the end 55 of a crank arm 60. As the crank arm is rotated in a counterclockwise direction, as viewed in Figure 8, the roller 59 engaging the side of the slot 58 in the lever 52 will cause the same to move about the fulcrum 53 and reciprocate the slide 17 60 toward the right.

45 The crank arm 60, as shown in Figure 3, is secured to a shaft 61 which has a spur gear 62 fixed therewith in mesh with a rack bar 63. The rack bar 63, as shown in Figure 9, has a piston 64 secured to the end thereof and slideably mounted in a cylinder 65. Upon admission of fluid pressure to opposite ends of the cylinder 65 the lever 52, and thereby the slide 17, may be oscillated to alternately position different groups of work pieces 65 in operative relation to the broach rams.

50 A pair of locking plungers 66 and 67 are provided for locking the slide 17 in either one of its two positions. These plungers, as shown in Figure 9, have rack teeth formed thereon which intermesh with a gear 68 which is secured to the

5 shaft 61. It will be noted from Figure 8 that the roller 59, during the last portion of its movement, will not effect any movement of the lever 52, thereby providing sufficient lost motion whereby the slide 17 will be substantially at rest when the 5 plungers are interengaging the respective slots 69 and 70 in the slide. Thus, the piston 64 serves to unlock the slide, move it to a new position and relock it in a single stroke thereof.

55 A mechanism has been provided for automatically loading the work holders in timed relation to the movement of the broaches and comprises an indexable carrier, indicated generally in Figures 3, 5 and 7 by the reference numeral 71, which is supported on the shaft 72. This carrier 10 15 consists of four wheels 73, each of which is keyed to the shaft 72 and each having eight work receiving bosses 74, each of which has associated therewith a plurality of pins 75 which are so located as to engage locating surfaces in the work piece 20 whereby the work piece will be so oriented that a slot will be broached therein in predetermined relation to the remaining surfaces on the work piece. It will be understood, of course, that any other suitable means may be utilized for orienting 25 the work pieces, which will depend upon the size and shape of the work.

30 The operator merely loads the work on the bosses as they reach the work loading position 74A and automatic means are provided for unloading the work into the work holders. Means are provided for successively indexing the work carrier once for each stroke of the ram.

35 This means comprises a pawl 76 which is pivotally mounted on a pin 77 carried by a reciprocable member 78. A spring pressed plunger 79 continuously urges the pawl in a counterclockwise direction to maintain engagement of the free end of the pawl with cross pins 80, projecting from the side of one of the wheels 73. When the 40 slide 78 is moved to its extreme position to the right of that shown in Figure 3, the pawl 76 will move to the position indicated by the dash and dot lines, the beveled end 81 of the pawl causing it to engage and pass beneath the next pin. 45 When the slide is retracted, the wheels will be indexed to position the next set of work pieces in front of the work holders.

50 The slide 78 has an upwardly extending boss 82 to which is fixedly connected a bifurcated member 83 carrying a pin 84, which passes through a link 85. The link 85 is pivoted at 86, as shown in Figure 4, and connected at the other end by a pin 87 to a plunger 88. This plunger has a cross pin 89 near the inner end thereof which engages 55 in a cross slot 90 formed in a tubular member 91. This tubular member has an inner spring 92 which engages the end of plunger 88, and an outer spring 93 which is positioned between a fixed shoulder 94 and a shoulder 95 formed on the tubular member, 60 whereby it is continuously urged in a direction to move the roller 96 toward the vertically moving ram. This movement is limited, however, by slide 78 engaging an abutment 97, as 65 more particularly shown in Figure 3.

65 The roller 96, as shown in Figure 2, is adapted to be engaged by a V-shaped dog 98 carried by the ram 14. In other words, as the ram 14 moves downward, as on a cutting stroke, the dog 98 will engage the roller 96 about midway of the ram 70 stroke and thereby through the spring 92 and lever 85 cause a reciprocation of the slide 78. The same will be true during an upward stroke of the ram. In other words, the carrier is indexed twice during one reciprocation of the ram 14. 75

The reciprocable slide 18, in addition to carrying means for indexing the carrier 71, also carries means for moving the work from the carrier into the work holders. Each wheel consists of two side plates 99 and 100, which are sufficiently spaced to permit a finger 101, as shown in Figure 5, to reciprocate between the plates in such a manner that when the member 18 is retracted, the end 102 will be behind the work receiving boss 74, and upon advance of the member 18, the end of the finger 102 will push the work piece 15 into a work receiving passage 18. The finished work piece in the passage will simultaneously be pushed on through, and a chute 103 is so located as to receive the falling finished work pieces and conduct them to the opening 104 where they will be deposited in any suitable container. As shown in Figure 4, there are four of these fingers, one for each wheel.

20 A detent mechanism shown in Figure 7 has been provided to insure accurate positioning of the work carrier so as to accurately align the work with the passages in the work holders. This mechanism comprises a detent wheel 105 in the periphery of which is formed a plurality of arcuate-shaped notches 106 which are adapted to be engageable by a roller 107 carried in the end of a spring pressed lever 108.

The machine may be hydraulically operated and one form of hydraulic circuit which may be utilized for this purpose is shown in Figure 10. A pump 109, having an intake 110 through which oil is drawn from a suitably positioned reservoir 111, is utilized for supplying fluid under pressure to the hydraulic circuit. The pump is connected by a delivery channel 112 to a valve 113 which is utilized as a start and stop valve by shifting plunger 114 to different positions, this plunger also being movable to a third position by hand 40 for reversing the direction of operation of the rams, if such should be found necessary.

In the running position, however, which is that shown in Figure 10, the pump delivery channel 112 is connected through a cannelure 115 in valve 45 plunger 114 and channel 116 to port 117 of valve 118 which functions as a form of interlock valve to insure that the work supporting slide has completed its shifting movement from one broaching station to the other before the rams start their 50 next stroke.

Between this interlock valve and the hydraulic motors which operate the rams is a pair of reversing valves, one for each motor, which are adapted to be simultaneously trip actuated by 55 the respective rams. Shifting of the reverse valve does not, however, cause an immediate change in the direction of ram movement, there being a slight delay to permit shifting of the work support. The interlock valve serves as a 60 means to provide this delay because the valve is coupled to the work support and is not shifted until the work support has almost reached the end of its stroke.

In the hydraulic diagram the reversing valves 65 have just been trip actuated to the position shown to change the direction of flow in the channels leading to the respective motors, but the interlock valve is still awaiting completion of the shifting of the work support.

70 When the interlock valve plunger is finally shifted it will be moved to the left of the position shown and the port 117 will then be connected through cannelure 119 in valve plunger 120 to channel 121, which leads to port 122 of valve 123 75 which serves to reverse the direction of fluid flow

through channels 124 and 125 connected to cylinder 126 which has a contained piston 127 operatively connected to the broaching ram 12. In the position shown, the port 122 is connected by cannelure 128 formed in valve plunger 129 to channel 125 whereby the pressure fluid will enter the upper end of cylinder 126 to cause downward movement of piston 127 and connected ram 12. The fluid in the lower end of the cylinder will escape through channel 124, cannelure 130 formed in valve plunger 129, and channel 131 to valve 132 which has a valve plunger 133 formed similar to valve plunger 129.

The valve 132 serves to control the direction of flow in channels 134 and 135 which lead to cylinder 136 having contained piston 137 which is operatively connected to the other broach ram 11. In the position shown, the cannelure 138 in plunger 133 connects channel 131 to channel 135 whereby the fluid escaping from the lower end of cylinder 126 is introduced into the lower end of cylinder 136, causing upward movement of piston 137. The fluid escaping from the upper end of cylinder 136 will pass through the channel 134 to the cannelure 139 in plunger 133, 25 which will connect it through channel 140 to port 141 of valve 118. This port is connected by cannelure 142 to channel 143 which terminates in port 144 of valve 113. When this valve is in a running position the port 144 is connected by cannelure 145 to the return channel 146 which has a relief valve 147 therein which is set to maintain a predetermined back pressure in the system and insure that all of the channels are kept filled with oil. 30

The valve plunger 129 is shifted by a ball-ended lever 148 which fits in a notch 149 formed in the end of the plunger, the lever being supported on the end of a shaft 150.

Similarly, the plunger 133 is shifted by a ball-ended lever 151 which interfits in a notch 152 formed in the plunger 133 and supported on a shaft 153. The shafts 150 and 153 may be operatively connected to trip levers 154 and 155, mounted as shown in Figure 11 on the front 45 of the machine adjacent the sides of the rams for actuation by suitably formed trip dogs 156 and 157 respectively. These dogs are so positioned that both trip levers, and thereby the connected valve plungers, will be shifted substantially at the same time. Another dog is provided on each ram whereby at the other end of each ram stroke both trip levers will be actuated. 50

In the position of the valves shown in Figure 10 the ram 14 is ready to move down and the ram 13 ready to move up. These rams will reach the positions shown at substantially the same time and will shift through the trip mechanism both plungers 129 and 133 to the positions shown 60 in Figure 10.

Prior to this, both plungers 129 and 133 were to the right of the position shown, while the interlock valve was still in the position shown. Under these conditions the fluid passed from 65 pressure port 117 through cannelure 119 and channel 189 to port 190 of reverse valve 132. This valve connected port 190, through cannelure 191 and channel 134, to upper end of cylinder 136 to cause the downward movement 70 of the piston 137 and the connected ram 13. Fluid escaping from the lower end of cylinder 136 passed through channel 135, cannelure 138 and channel 190' to valve 123 where it was directed by cannelure 164' to channel 124 leading 75

to the lower end of cylinder 126. The piston 127 thus moved upward when the piston 137 moved downward.

Fluid escaping from the upper end of cylinder 126 passed through channel 125 and cannelle 128 of valve 123 to the return line 129, which is connected by cannelle 142 of the start and stop valve 120 to the return line 143.

Assuming the fluid to be flowing through the 10 circuit, as last explained, it will be evident that when the reversing valves are trip actuated into the positions as shown in Figure 10 that the pressure port 190 will be disconnected from channel 134 and movement of the rams will stop.

15 At the time it is so disconnected the plunger 133 will be shifted in such a manner as to connect port 190 to channel 190', which at this time is connected by cannelle 164' to port 164 and channel 163 to a relief valve 161. The channel 20 163 has a branch 159 through which fluid is delivered to cause a shifting movement of the work support to place unfinished work pieces in an operative position with respect to the ram 14. In the position of the parts shown, the fluid 25 from channel 159 will pass through cannelle 158 and channel 179 to valve 168.

The valve 168 has a plunger 169 which is connected to a ball-ended lever 170 mounted on shaft 171. This shaft is operatively connected 30 to a trip lever 172 mounted on the front of the machine adjacent the other trip levers for actuation by a trip dog 173. It will be noted from Figure 10 that the valve plunger 169 has a spring 174 interposed between the end of the 35 plunger and the end of the valve housing 168, which tends to urge the plunger in a direction to disconnect the cylinder 65 from the rest of the system. Due to this spring, the valve 169 is only opened for a short time and that is when 40 it is being held open by the dog 173. This dog is so positioned as to operate at the same time as the other dogs, so that the fluid which is now being delivered to channel 179, will be connected by the cannelle 178 to channel 171 and thereby 45 to the left end of cylinder 65, causing shifting of piston 64 and of the work slide to a new broaching position.

Fluid will exhaust from the other end of cylinder 65 through channel 176, which at this time 50 is connected by cannelle 175 to channel 166. This channel leads to port 180' of valve 118. At this moment the valve plunger 120 is still in the position shown in Figure 10, so that port 180' is connected by cannelle 181 to channel 55 182, which, in turn, is connected by cannelle 183 in valve plunger 114 to the return channel 146 which empties into the reservoir 111.

The plunger 120 of valve 118 is connected by a ball-ended lever 184 to shaft 185 and the 60 valve may be so positioned that this shaft, as shown in Figure 3, extends to a position adjacent the periphery of a dog wheel 186 keyed to the end of shaft 61. The end of shaft 185 may be provided with a trip arm 187, which is adapted 65 to be engaged by a trip dog 188 carried or supported in the periphery of the dog wheel so that upon rotation of the shaft 61, caused by movement of the piston 64, the shaft 185 will be oscillated as the piston 64 completes its movement, which means that the work holder has completed its movement to a new broaching position.

Since the work is now positioned for another broaching operation, the oscillation of shaft 185 75 will shift the valve plunger 120 to the left of the

position shown, thereby connecting the pressure port 117 to channel 121 leading to valve 123. Since the plunger 129 of this valve is already in position to connect port 122 to upper end of cylinder 126, ram 14 is starting its downward movement and ram 13 its upward movement.

In conclusion, the operation of the machine may be briefly described as follows:

The operator merely loads the work pieces in the carrier from which a specified group is automatically transferred during each stroke of the ram into a work holder which has sufficient capacity to permit the loading of one group of work pieces while a second group is having a stock removing operation performed thereon. 10 From Figure 4 it will be noted that the rams 13 and 14 are spaced apart a distance substantially equal to the width of one ram, thereby the unloading and loading operations are performed intermediate the rams. Each ram has four 20 broaching tools 192 secured thereto, but it will be apparent that the rams could be made wider to accommodate a greater number of broaches and that they could be spaced further apart and the work holder may be made longer if it is desired to increase the capacity of the machine without changing the principles of operation. Attention is invited to the fact that backing-up plates 193 are adjustably positioned opposite each ram and that each of these plates has a 30 beveled corner 194 whereby as the work holder shifts in either direction, the rear end of the work pieces will engage the beveled edge and gradually be moved axially to a predetermined 35 position which will determine the depth of the slot to be formed in the work piece. In other words, the rear end of the work piece is utilized as a locating surface from which the depth of the slot is measured.

The machine is started by the operator shifting 40 the start and stop valve 114 into the running position shown in Figure 10 against the compression of spring 195, and from then on the rams reciprocate in opposite phased relation, and at the end of each stroke there is a slight 45 dwell while the work holder is shifted from one position to the other. In the middle of each stroke of the ram, the work holder is automatically unloaded and loaded, whereby the operator's duties are confined to simply loading the 50 work carrier.

The valve 114 is shifted by a bell crank 196 which is operatively connected to a handle 197. When the valve is shifted into the position shown, a spring pressed latch 198 holds it in 55 that position against the spring 195. To stop the machine it is merely necessary to rotate the lever 197 in a counterclockwise direction to release the latch 198 and the spring 195 will then shift the valve to a stop position which will connect the delivery channel 112 of pump 109 with the return line 146.

There has thus been provided an improved automatic machine for the purpose disclosed, which has improved means for unloading and 65 loading a plurality of work pieces without materially reducing the actual cutting time of the machine.

We claim:

1. In a broaching machine having a support, 70 a work holder reciprocably mounted on said support, means to secure a plurality of work pieces in said work holder, a broaching ram having a plurality of broaches thereon, equal in number to the number of said work pieces, means to re- 75

5 ciprocate said work holder between a working position and a loading position, and work feeding means at said loading position to simultaneously insert a plurality of unfinished work pieces in said work holder and remove the finished work pieces.

2. In a broaching machine having a plurality of broaches, the combination of a work holder for presenting a work piece to each of said 10 broaches comprising a slide, a plurality of work clamping members carried by said slide, said members having their upper surfaces arranged in stepped relation, a fixed support, and plungers mounted in said support with their ends in 15 stepped relation for simultaneous engagement with said stepped surfaces upon movement of the slide to a broaching position.

3. In a broaching machine having a plurality of broaches, the combination of a work holder 20 having means for supporting and presenting work pieces to said broaches comprising a slide movable between a loading position, and a broaching position, means for automatically clamping the work during movement of the slide 25 to a broaching position comprising a plurality of clamping members, each member having a surface thereon inclined to the direction of slide movement, said surfaces being arranged in stepped relation, a fixed support, plungers arranged in said support in a similar stepped relation whereby each plunger will engage an inclined surface simultaneously during movement of the slide to a broaching position whereby a plurality of work pieces may be individually 30 clamped at the same time.

4. In a broaching machine, the combination of a first plurality of broaches and a second plurality of broaches, power operable means for moving the first set of broaches through a cutting stroke and returning the second set of broaches through a non-cutting stroke simultaneously, a common slide for supporting and presenting work to each set of broaches, means to automatically load work in one portion of said 45 slide while work in the other portion is being broached, means to move the slide to present the newly loaded work to one set of broaches and withdraw the finished work from the other set of broaches, and means to simultaneously 50 clamp one set of work pieces and unclamp the finished work pieces during movement of said slide.

5. In a broaching machine having a pair of rams simultaneously movable in opposite directions, and means to simultaneously reverse the direction of movement of each ram, the combination of a slide for alternately presenting work to said rams, means for automatically loading 55 said slide with unfinished work pieces during reciprocation of the rams, and means for automatically shifting said slide to position the unfinished work pieces in a broaching position during reversal of said rams.

6. In a broaching machine having a pair of oppositely movable rams, and broaching tools carried by said rams, the combination of a work supporting slide, movable from a broaching position with respect to one ram to a broaching position 60 with respect to the other ram, means for automatically reciprocating said slide, including a fluid operable piston, a shaft, rack and gear connections between said piston and shaft, a lever connected to a fixed pivot at one end and at the 65 other end to said slide, and a crank connected to

said shaft for oscillating said lever and thereby moving said slide.

7. In a broaching machine having a pair of broach carrying rams and a slide for alternately presenting work to said broaches, the combination of means for automatically loading said slide with unfinished work pieces including an indexible work carrier, and means trip operable by one of said broaching rams to move the work from said carrier to said slide during each broaching operation.

8. In a broaching machine having a pair of broaching rams, broaching tools carried by said rams and a common slide for presenting work pieces to the broaches, the combination of a 15 mechanism for automatically loading said slide including an indexible work carrier, means trip operable by one of said rams for moving work from said carrier to said slide and including a reciprocable member, and means operable by said 20 member during its return stroke to effect indexing of said carrier.

9. In a broaching machine having a pair of broaching rams, broaching tools carried by said rams and a common slide for presenting work 25 pieces to the broaches, the combination of a mechanism for automatically loading said slide including an indexible work carrier, means trip operable by one of said rams for moving work from said carrier to said slide and including a reciprocable member, means operable by said 30 member during its return stroke to effect indexing of said carrier, and a spring pressed detent mechanism for accurately positioning said carrier in a work loading position with respect to 35 said slide.

10. In a broaching machine, the combination of a pair of rams alternately reciprocable in a given plane, a work holder movable in said plane normal to the direction of movement of said rams for alternately presenting work thereto, and means to automatically load a portion of said work holder with unfinished work pieces while a plurality of other work pieces are being held by said holder in operative position to one of said 45 broaching rams.

11. In a broaching machine having a pair of broaching rams movable in a given plane and in opposite phased relation, the combination of a work holder movable in said plane in a direction normal to the axis of movement of said rams, a work carrier rotatably mounted on an axis lying parallel to the direction of movement of said work holder, said work carrier being positioned intermediate said broaching rams whereby work may be loaded from said carrier into said work holder during each broaching stroke of the rams.

12. A duplex broaching machine of the character described including a pair of spaced broach actuating rams providing a pair of broaching stations, a work loading mechanism disposed intermediate said rams, a work supporting member having a plurality of work supports, and means for alternately presenting an individual work support at the loading mechanism and at one of the broaching stations.

13. A duplex broaching machine of the character described including a pair of spaced broach actuating rams providing a pair of broaching stations, a work loading mechanism disposed intermediate said rams, a work supporting member having a plurality of work supports, means for alternately presenting an individual work support at the loading mechanism and at one of the broaching stations, each of said work supports 75

being individual to a particular broaching station.

14. A broaching machine of the character described, including a pair of spaced broach operating rams and a loading mechanism disposed intermediate said rams, a member mounted for reciprocation intermediate the rams, spaced work supports carried by said member and individual as respects individual rams, and means for shifting said member to present one of said supports in operative relation to its individual ram and simultaneously present the other work support to the loading mechanism for supply of a work piece to said supports.

15. 15. A broaching machine including a bed, a pair of broach receiving rams rising therefrom in spaced relation one to the other, a table member reciprocable on the bed for alternate presentation of terminal portions thereof to the respective rams, and means providing a work loading and discharging station intermediate the rams adjacent the path of movement of the table whereby when either terminal portion of the table is disposed in cooperating relation with one of the rams, the opposite terminal portion will be operatively positioned at the load and ejecting station substantially as and for the purpose described.

16. The combination with a broaching machine including a support, a pair of broaching rams reciprocably mounted thereon and a work holder slide transversely shiftable on the support having work support portions individual to the respective rams, of means for supplying work pieces

to the respective individual work supports when translated to a position remote from their rams, said means including an indexible work carrier having a plurality of work receiving stations, means for indexing the carrier to shift an individual station from a loading position into a position aligning a work piece thereon with a work support, and means for effecting a reciprocation of the carrier to position a supported work piece in operative relation to the translatable work support.

17. The combination with a broaching machine including a support, a pair of broaching rams reciprocably mounted thereon and a work holder slide transversely shiftable on the support having work holding positions individual to the respective rams, of means for supplying work pieces to the respective individual work holders when translated to a position remote from their rams, said means including an indexible work carrier having a plurality of work receiving stations, means for indexing the carrier to shift an individual station for a loading position into a position aligning a work piece thereon with a work support and, means for effecting a reciprocation of the carrier to position a supported work piece in operative relation to the translatable work support, and means for effecting a retraction of the carrier in advance of the translatory movement of the support.
